VOTING MACHINE HAVING PRIMARY PARTY VOTING MECHANISM AND ENFORCED VOTE CASTING INTERLOCKS

Ransom F. Shoup, Bryn Mawr, Pa., assignor to The Shoup Voting Machine Corporation, New York, N. Y., a corporation of New York

Application October 26, 1956, Serial No. 618,503

13 Claims. (Cl. 235—55)

My invention relates to a voting machine of the general type illustrated in Shoup Patent No. 2,054,102 of September 15, 1936, which is in extensive use throughout the United States under the name Shoup Voting Machine.

One object of the invention is to produce an improved voting machine of the type set forth.

Voting machines of the type referred to are used for selecting intra-party candidates in primary elections and for electing inter-party candidates in general elections.

In order to avoid the necessity of setting up one or more machines for each political party participating in a primary election, it has heretofore been proposed to provide means whereby the voter himself, or the election officer attending the machine, may instantaneously set the machine according to the party affiliations of the voter desiring to use the machine. One such arrangement is disclosed in Shoup Patent No. 2,251,254 or No. 2,251,255, both issued on July 29, 1941.

The voting machines disclosed in these patents were set and re-set for use by successive voters of different political parties by actuating one or another of a number of selector knobs each of which served to lock all voting spindles except those of the party with which the voter wishing to use the machine is affiliated.

Because the number of voting spindles which are to be temporarily locked can be large, and because, to lock these voting spindles, it was necessary to move certain parts from one position to another, and because of the weight and friction involved, the parts to be moved were counterbalanced by a relatively strong spring without which it would be difficult, if not impossible, to move said parts. If, in such an arrangement of this type, the number of parts to be moved is large, the spring may be inadequate and resetting the machine requires much effort. If the number of parts is small, the spring will be too powerful and the parts were moved violently and with attendant shock. To use different springs for different settings of the machine is not practical.

It is therefore a still further object of the invention to produce an improved voting machine which can be re-set for use by successive voters of different parties, instantly and with very little exertion.

The voting machines to be used are prepared according to the number of parties and the number of candidates in the field. This preparation is made by, or under, the supervision of an official who is known as the custodian. When in use, the machines are under the supervision of an attendant known as the election officer.

It is necessary that the machine be protected against improper voting between the time the custodian has finished preparing it, and the beginning of the voting. It is also necessary that the election officer, and the watchers for the different parties, be able to see that all of the vote counters are set at zero before the first vote is cast and that the vote counters be concealed before the first vote is cast, and it is necessary that the vote counters remain concealed until after the last vote is cast.

It has heretofore been proposed to lock the voting

2

machine in a manner which required the use of a key to unlock the machine to allow the voting to begin. In the confusion that is often present and because of human frailty, the election officer in charge of the machine may not be able to find the key, or the key may not work, etc. with consequent delay and inconvenience.

It is therefore a still further object of the invention to produce an improved voting machine which can be adequately locked against tampering, but which can be placed in voting position by the election officer without the use of any key.

These and other objects are attained by my invention as set forth in the following specification and as illustrated in the accompanying drawings in which:

15 Fig. 1 is a fragmentary, front elevational view of a voting machine embodying my invention, certain parts being broken away to show details of construction.

Fig. 2 is a sectional view taken on line 2—2 on Fig. 1.

20 Fig. 3 is an enlargement of the shutter structure shown in the upper left hand portion of Fig. 2, and it shows the shutters in their counter-covering position.

Fig. 4 is similar to Fig. 3, but it shows the shutters in their counter exposing position.

25 Fig. 5 is an enlarged, fragmentary, sectional view taken on line 5—5 on Fig. 1.

Fig. 6 is an enlarged, fragmentary, sectional view taken on line 6—6 on Fig. 6.

Fig. 7 is a fragmentary, sectional view taken on line 7—7 on Fig. 6.

30 Fig. 8 is an enlarged, fragmentary, sectional view taken on line 8—8 on Fig. 2.

Fig. 9 is an enlarged, fragmentary, perspective view of the shutters locking mechanism.

Fig. 10 is an enlarged, exploded, fragmentary perspective view showing details of construction of the shutters.

Fig. 11 is a fragmentary, sectional view taken on line 11—11 on Fig. 5.

Fig. 12 is an enlarged, fragmentary, elevational view looking in the direction of line 12—12 on Fig. 5.

40 Fig. 13 is an enlarged, fragmentary sectional view taken on line 13—13 on Fig. 12.

Fig. 14 is an enlarged, fragmentary, sectional view taken on line 15—15 on Fig. 14.

Fig. 15 is an enlarged, fragmentary, sectional view taken on line 15—15 on Fig. 14.

45 Fig. 16 is an enlarged, fragmentary, sectional view taken on line 16—16 on Fig. 12.

Fig. 17 is an enlarged, fragmentary, sectional view taken on line 17—17 on Fig. 12.

Fig. 18 is a fragmentary, sectional view taken on line 18—18 on Fig. 13.

Fig. 19 is a rear elevational view showing some of the parts of a voting machine to which the invention is applied.

55 Fig. 20 is an enlarged, fragmentary view showing the position of the parts when the machine is in curtain closed, or voting position.

Fig. 21 is similar to Fig. 20 except that it shows the parts in the curtain open or non-voting position of the machine.

60 Fig. 22 is a reduced, top plan view of a voting machine to which my invention is applied.

Fig. 23 is a fragmentary view showing details of construction.

65 As best shown in Figs. 1, 19, 20 and 21, a voting machine includes voting spindles S, which are operatively connected to vote counters C and which are actuated by keys, not shown. The structure and operation of the voting spindles and the vote counters are disclosed in Pat. No. 2,054,102, as well as in some of my other patents, and therefore are not shown nor described. Voting spindles S are provided with butterfly cams B which,

upon rotation of the voting spindles, in clockwise direction, as viewed in Fig. 20, engage and raise the corresponding voting spindle return members 10, as shown in broken lines in Fig. 20. When return members 10 move down to the solid line position of Fig. 20, they rotate butterfly cams B in the opposite direction and return voting spindles S to their ready to use position. To control the operation of the voting spindles S, each voting spindle return member 10 is provided with a rigidly connected bottom bracket 14 which has a rigidly connected arm 16 which carries a rigidly connected roller 18. In the non-voting position of Fig. 21, roller 18 rides on the flat, slightly inclined surface 20 of a cam bar 22. In this position, roller 18 cannot move downwardly and therefore return member 10 cannot be raised and the corresponding voting spindle cannot be turned. To enable the voter to move the voting spindle return member upwardly, cam bar 22 is provided with notches 24 and means is provided, for moving cam bar 22 in a direction to bring notches 24 into registration with rollers 18. In Fig. 20, one roller 18 is shown as it begins to move down into a notch 24 and therefore its corresponding voting spindle return member 10 may begin its upward movement by rotation of its corresponding butterfly cam B. When cam bar 22 is moved in the opposite direction, vertical edge 25 of notch 24 engages arm 18, as shown in broken lines in Fig. 20, and moves bracket 14, arm 16 and roller 18 out of notch 24 and back to the position of Fig. 21 in which return member 10 is again locked against upward movement. The mechanism which opens or closes the voting machine curtain and which operates cam bar 22 will hereinafter be referred to. For the present it is sufficient to state that cam bar 22 is movable, with the closing of the curtain, to the position of Fig. 20, in which the voting spindles can be used, and with the opening of the curtain to the position of Fig. 21 in which the voting spindles are locked.

In order to enable the custodian to lock the machine after he has prepared it and until the shutters are lowered to permit the voting to begin, I provide a locking mechanism which includes an angle slide member 30 and a lever 32 which is fulcrumed at 34 and the free end of which engages a hole 36 in the horizontal wall of the slide as shown in Fig. 12. Lever 32 is pivoted at 38 to the lower end of an arm 40, the upper end of which is pivoted at 42 to a link 44 which is pivoted at 46 to a handle 48. See Fig. 13. By manipulating handle 48, slide 30 may be moved to the right or to the left, as viewed in Fig. 12.

In manual operation, movement of slide 30 to the right, as viewed in Fig. 12, disengages a pawl, not shown, which normally engages a ratchet, also not shown, on cam bar 22, so as to release the cam bar for movement to the left with the closing of the curtain. In electrically operated machines, movement of slide 30 to the right in Fig. 12 closes a normally open switch, not shown, which energizes motor M in a direction to close curtain 33. In either case, the vertical walls of slide 30 is provided with a hole 50 which, in the locked position of the machine is engaged by the end 52 of pin 24 which is mounted for movement through a hole in a fixed portion 56 of the frame of the machine. Pin 54 is biased away from hole 50, or to the right in Fig. 5, by a spring 58 and is provided with an enlarged boss 60 which is adapted to pass through notch 62 in main cam bar 64 which is movable jointly with cam bar 22, in a manner and for a purpose which form no part of the present invention. It is sufficient to say that, when cam bar 22 is in its locked, or non-voting, position of Fig. 21, notch 62 in cam bar 64 will register with boss 60 and vice versa. In other words, in the locked position of the machine, notch 62 in cam bar 64 and hole 50 in slide 30 will both be in registration with, and will be engaged by, pin 54 and notches 24 in cam bar 22 will be out of registration with roller 18 of voting spindle return mem-

bers 10. Therefore, to release the machine for use, pin 54 must be disengaged from slide 30 and from cam bar 64. The manner in which this is done is shown in Figs. 7 and 8 and is hereinafter explained.

The machine is also provided with shutters 68 which are carried by plate 70 and which are movable to the lower position of Fig. 3, to cover vote counters C or to the upper position of Fig. 4 to expose the vote counters. Shutters 68 are movably mounted relative to the upper wall 74 of a Z-shaped member (see Figs. 5 and 10), by means of pins 76 which are carried by plate 70 and engage slanted slots 78 in wall 74. Plate 70 also has slanted slots 80 through which pins 82 carried by wall 74 pass to be engaged by cotter pins, not shown, movably to assemble the shutters to wall 74. By this arrangement, when wall 74 is moved horizontally in one direction the shutters will move upwardly and laterally in one direction and when wall 74 is moved in the opposite direction shutters 72 will move downwardly and laterally in the opposite direction.

In order to control movement of wall 74, and, hence, the movement of the shutters, intermediate wall 86 of the Z-shaped member referred to is also provided with teeth 88 which are selectively engageable with the end 90 of dog 92 or with the end 94 of dog 96. Dogs 92 and 96 are freely rotatable on pins 98 which project from frame portion 56 and are normally biased in a direction to engage teeth 88 by springs 99. Dogs 92 and 96 are selectively disengaged from teeth 88 by means of pin 100 which is carried by slide 102 which is movable relative to wall 74 of the Z-shaped member to bring pin 100 into position to depress the inner end 104 of dog 92 or the inner end 106 of dog 96 to disengage one or the other of said dogs from teeth 88. In Fig. 9, dog 92 is shown disengaged from, and dog 96 is shown engaged with, teeth 88 and therefore, the Z-shaped member can be moved to the right as viewed in Fig. 9. It is understood that, if slide 102 is moved to the right, pin 100 will depress the end 106 of dog 96 and will disengage it from teeth 88 so that the Z-shaped member may now be moved to the left as viewed in Fig. 9. Slide 102 is provided with a ratchet 112 which is adapted to be engaged by a pawl 114 which is freely rotatable on pin 116 which also projects from frame portion 56. Pawl 114 is normally biased into engagement with the ratchet by spring 118. By inspection of Fig. 9, it will be seen that slide 102 can be moved to the right as viewed in Fig. 5 regardless of the position of pawl 114, but that slide 102 cannot be moved to the left in Fig. 9 unless pawl 114 has first been disengaged from ratchet 112.

Slide 102 may be moved in either direction, by means of a lock 120 provided with a crank 122 which is secured to the slide and is adapted to be rotated by a key, not shown. Lock 120 is conventional and is so constructed that the key may be inserted and removed only when the lock barrel is in a given position and so that the slightest turn of the key in the lock will prevent withdrawal of the key. This lock is known as the election officer's lock. As previously stated, pawl 114, in the position of Fig. 9 prevents movement of slide bar 102 to the left while permitting movement of the slide to the right of its position in Fig. 9, or to a position in which end 94 of dog 96 is disengaged from teeth 88. In order to be able to move slide 102 to the left, or back to the position of Fig. 9, I provide another lock 124 which is known as the custodian's lock. This lock is provided with a finger 126 which, when lock 124 is turned in clockwise direction, as viewed in Fig. 9, will engage an extension 128 of pawl 114 and will lift the pawl out of engagement with ratchet 112. This permits movement of slide 102 to the left, or back to the position of Fig. 9 in which pin 100 will disengage dog 92 from teeth 88.

In order to lock all voting spindles except those pertaining to the party with which the voter desiring to use the machine is affiliated, I provide the mechanism best shown in Figs. 5, 13, 14 and 15. This machine includes

an index plate 140 which is provided with a number of stations which are marked R for Republican, D for Democratic, P for Progressive and so on, and I provide a pointer 142 which is selectively movable to one or another of these stations. If the voter is republican, handle 142 is moved to register with R, and if he is a democrat, the handle is moved to register with D and so on. Handle 142 is connected through suitable links and levers which are generally referred to by numeral 144 to arm 146 and the arrangement is such that, when handle 142 registers with R on index plate 140, arm 146 is in its uppermost position, or the position shown in Figs. 13 and 18, and vice versa. As will be seen from Fig. 12, arm 146 is operatively connected at 148 to one arm 150 of a bell crank which is pivoted at 152 to a fixed frame portion 154 and the other arm 155 of which is operatively connected at 156 to a serrated bar 158. By this arrangement, when arm 146 is moved downwardly, serrated bar 158 will move to the right as viewed in Fig. 12 and vice versa. Serrated bar 158 is provided with a number of clips equal to the number of political parties in the field, only two of these clips 160 and 162 being shown in Fig. 14. As will be seen from Figs. 14 and 15, each of the clips includes a vertical wall 164 and a horizontal top wall 166 which has an opening 168 therein. Wall 164 of each clip is clamped onto the serrated bar 158 by a set screw or other means 169. By this arrangement, the clips can be arranged in any desired spaced relation along serrated bar 158. Now, referring back to Figs. 15 and 20, it will be seen that the roller 18 of each voting spindle return member 10 is provided with a feeler formed of vertical wall 170 and a horizontal wall 172 which will overhang top wall 166 of any clip 162 or 160 which is brought into registration therewith, as best shown in Figs. 14 and 15. It will be recalled that, for a voting spindle return member 10 to move upwardly when a voting spindle is turned into vote counter actuating position, its corresponding roller 18 must move downwardly into corresponding notch 24 in cam bar 22. It therefore follows that, if a clip is so located on bar 158 that the top wall 172 of the feeler referred to registers with the solid portion of the top wall 166 of a clip, as in the position of clip 162 in Fig. 14, the corresponding roller 18 cannot move downwardly and the corresponding voting spindle return member cannot move upwardly and the corresponding voting spindle will be locked out regardless of the position of any, or of all, of the other parts of the machine. On the other hand, if a clip is so located on serrated bar 158 that top wall 172 of its feeler registers with opening 168, in the top wall of the clip, as in the position of clip 160 in Fig. 14, the corresponding roller 18 can move into corresponding notch 24 and the corresponding voting spindle return member can be moved upwardly and the corresponding voting spindle can be moved in vote counter actuating direction. This is on the assumption that the other parts of the voting machine are in vote-permitting position.

In actual use, the custodian so arranges the clips on bar 158 that, when handle 142 is in position R, the clip or clips associated with the return members of the voting spindles assigned to the Republican party will be in positions corresponding to the position of clip 160 in Fig. 14, and the clips associated with the return members 10 of all of the other voting spindles, will be in positions corresponding to the position of clip 162 in Fig. 14. If handle 142 is moved to position D, the clips associated with the Democratic party will assume positions corresponding to the position of clip 160 in Fig. 14 and so on.

In order to lock handle 142 against movement while the voting spindles of the party indicated by the position of said handle are being used, the lower end of arm 146 has a series of vertically spaced holes 176 and I provide cam bar 22 with a pin 178 which, when cam bar is moved to the position of Fig. 12 will engage one or another of holes 176. Pin 178 is spring loaded so that if, for any reason, it is not in perfect alignment with one of holes

176, there will be no damage when cam bar 22 is moved to its extreme lefthand position. Intermediate wall 86 of the Z-shaped member is provided with teeth 180 which are adapted to be engaged by a gear 182 the shank 184 of which passes through a slot 186 in the lower wall 188 of the Z-shaped member. In Fig. 8, the Z-shaped member is shown in its extreme right-hand position and, it will be understood that gear 182 can only be turned in counterclockwise direction to move the 10 Z-shaped member to the left. The bottom wall 188 of the Z-shaped member also has a slot 190 which is adapted to be engaged by the reduced proportion 192 of pin 54 and has an enlarged, round opening 196 which is adapted to be engaged by the portion of the body of the pin 54 which 15 is to the right of the reduced portion 192 as viewed in Fig. 5. When the reduced portion 192 of pin 54 is in slot 190, the Z-shaped member can be moved by rotation of gear 182 to the left or to the right according to whether dog 92 or dog 96 happens to be in engagement with teeth 188. When pin 54 engages enlarged opening 196, the Z-shaped member cannot be moved either direction regardless of the position of dogs 92 and 96. By inspection of Figs. 5 and 6, it will be seen that reduced portion 192 of pin 54, can only engage slot 190 when the pin is pushed 20 inwardly or to the left in Fig. 5, against the action of spring 58. It will also be seen that pin 54 cannot be pushed to the left in Fig. 5 unless hole 50 in latch 30 is in registration with the end 52 of the pin and unless notch 62 in main cam bar 54 is in registration with boss 60 of pin 54. On the other hand, when enlarged opening 196 is in registration with pin 54, spring 58 will move pin 54 to the right in Fig. 5 to disengage boss 60 from notch 62 in main cam bar 64 and to disengage the end 52 of the pin from hole 50 in latch 30.

35 In the drawings, the machine is illustrated as the parts would appear at the end of the election, or after all of the voters have voted and with the shutters 68 in their lower or vote counter covering position of Fig. 3. It is now necessary for the election officer and the watchers 40 of the participating political parties to look at the counters and record the totals for the various candidates. In order to raise the shutters so as to uncover the vote counters, the election officer puts his key in lock 120 and turns it in clockwise direction to move slide 102 to the right as viewed in Fig. 9. Movement of slide 102 to the right 45 disengages dog 96 from teeth 88, and permits movement of the Z-shaped member to the left as viewed in Figs. 9 and 10. Movement of slots 78 in wall 74 of the Z-shaped member of the left relative to pins 76 causes the shutters to move upwardly and to the left as viewed in Figs. 3 and 50 10 to expose the vote counters as shown in Fig. 4. It will be noted that once the election officer has turned his key in lock 120, he cannot take it out unless slide 102 is moved to the left in Fig. 9. But, because of the engagement of 55 pawl 114 with ratchet 112, slide 102 cannot be moved to the left and the election officer's key cannot be removed from the lock.

The machine is also provided with a normally open switch 200 and with comb bar 202 which has spaced teeth 204 which are adapted to be engaged by rollers 18 of the voting spindle return members 10 when they move arcuately in notches 24. By this arrangement, if any return member is raised, which takes place only if at least one voting spindle has been turned to, and kept in, voting 60 position, comb bar 202 will move to the left as viewed in Figs. 12 and 16 and will close switch 206. On the other hand, if the voter turns no voting spindle, or, having turned it to voting position he turns it back, comb bar 202 will not be moved or will be moved back to its inoperative position, as the case may be. In either case switch 206 will remain open. Switch 206 is in series with another switch, not shown, which is inside the machine and which must be closed to actuate motor M in a curtain opening direction. Therefore, if switch 206 is not closed, the curtain will not be opened and the voter will know

that he either did not move any voting spindle or that he inadvertently moved them back to non-voting position.

At the end of the election, the custodian closes the doors of the machine, not shown, and seals them. This is done in the presence of the various officers concerned and the machine is impounded for a prescribed period which varies from one jurisdiction to another. At the end of this period, the custodian breaks the seal and resets the vote counters to zero. He also puts his key in lock 124 and turns it to release pawl 114 from ratchet 112. The election officer's key may now be turned in counterclockwise direction, as viewed in Fig. 9 to move slide bar 102 to the left as viewed in this figure. The election officer's key can now be removed from the lock to be delivered, together with the locked and re-set machine, to the election officer at the next election.

When the machine is delivered to the voting place, cam bar 22 will be in the position of Fig. 21 in which return members 10 and, hence, the voting spindles, cannot be moved, latch 30 will be in its extreme left hand position of Figs. 12 and 23 in which normally open switch 31 remains open and curtain 32 cannot be closed; hole 50 in latch 30 will be engaged by end 52 of pin 54 and notch 62 in main cam bar 64 will be engaged by boss 60 on pin 54; shutters 68 will be in the upper, vote counter exposition of Fig. 4; dogs 92 and 96 will be in the position of Fig. 9; slide 102 will be in its extreme left hand position of Fig. 9, the Z-shaped member will be in its extreme right hand position of Figs. 6, 7 and 8; clips 160, 162, etc. will be so arranged on bar 158 that, when index 142 is in registration with R the clips associated with voting spindles assigned to the Republican party will occupy positions like the position of clip 160 and all other clips will occupy positions similar to the position of clip 162, and reduced portion 192 in slot 190 which, in turn means that end 52 of pin 54 cannot be disengaged from hole 50 in latch 30 and boss 60 on pin 54 cannot be disengaged from notch 62 in main cam bar 64.

After having noted that all vote counters stand at zero, the election officer turns gear 182 to the left as viewed in Fig. 8 to move the Z-shaped member to the left as viewed in Figs. 7 and 8 to lower the shutters to the vote counter concealing position of Fig. 3. This movement of the Z-shaped member brings large opening 196 into registration with pin 54 which is now biased to the right, as viewed in Fig. 5, to disengage the end 52 and boss 60 of the pin from holes 50 and notch 64. This releases latch 30 which may now be moved to the right in Figs. 12 and 23, to close switch 31, by manipulating handle 48 and releases main cam bar 64 which may now move to the left, jointly with cam bar 22, to bring the latter to the position of Fig. 20.

In a general election, clips 160, 162, etc. are either omitted or they are all arranged in positions similar to the position of clip 160 in which none of the return members 10 is locked out. In a primary election, the clips are so arranged that movement of index 142 to one position or another brings selected clips, or groups of clips, into positions similar to the position of clip 160.

At the end of the election, the election officer puts his key in lock 120 and turns it in clockwise direction to reverse the positions of dogs 92 and 96 and permit movement of the Z-shaped members to the right, as viewed in Fig. 9, or in shutter raising direction. But, because pin 54 engages large opening 196, as in Fig. 7, the Z-shaped member cannot be moved until pin 54 is pushed to the left in Fig. 5 to bring reduced portion 192 of pin 54 into slot 190. This, in turn, cannot be done unless latch 30 and main cam bar 64 are in the locked position of the machine in which the end 52 and boss 60 on pin 54 will enter hole 50 and notch 62 respectively. Once this is done and the Z-shaped member is moved to move the shutters to vote counter exposing position, it cannot be moved back because dog 90 will be in engagement with teeth 88. Also, because pawl 114 engages ratchet 112,

slide 102 cannot be moved to the left in Fig. 9 until the custodian operates lock 124 to disengage pawl 114, the election officer cannot remove his key.

After the vote counters have been read, the machine is impounded to be set for the next election after the impounding period is over.

What I claim is:

1. A voting machine including a plurality of vote counters, a plurality of voting spindles, each of said spindles being movable to a first vote casting position in which it actuates one of said counters and to a second, non-vote casting position, in which it does not actuate its corresponding vote counter, a vertically movable return member for each of said voting spindles, means operatively connecting each of said return members to a corresponding voting spindle whereby each return member is moved upwardly by movement of its corresponding voting spindle to its first position, and whereby the downward movement of said return member moves said corresponding voting spindle to its second position, an arm carried by each return member, each arm being disposed substantially normal to the vertical plane of movement of the corresponding return member and projecting substantially normal to said plane and each return member and its arm being so related that the arm must move downwardly simultaneously with the upward movement of its corresponding return member, a cam bar located in the path of movement of said arms and having spaced notches therein large enough to receive and permit downward movement of said arms, said cam bar being movable to a first position in which said notches register with said arms to permit downward movement of said arms and upward movement of said return members and to a second position in which said notches do not register with said arm and prevent movement of said arms and of their corresponding return members, and locking means for preventing downward movement of said arms and their corresponding return members and, hence, movement of the corresponding voting spindles even though said cam bar is in its first position, said locking means including an auxiliary bar located adjacent to and extending longitudinally of, said cam bar, a plurality of clips carried by said auxiliary bar, said clips having wall portions which protrude into the paths of movement of said arms, respectively, and means for clamping said clips in any desired spaced relation along said auxiliary bar, there being openings in said wall portions large enough to permit free passage of said arms whereby, when said clips are in a first location relative to said return members, said notches will register with the paths of movement of said arms to permit downward movement thereof and upward movement of said return members and, hence, the movement of said voting spindles to their first position, and whereby, when said clips are in a second location relative to said return members, said notches will not register with the paths of movement of said arms and prevents upward movement of said return members and the movement of said voting spindles to their vote-casting position.
2. The structure recited in claim 1 and means mounting said auxiliary bar for movement longitudinally of said cam bar, and actuating means for moving said auxiliary bar to various positions to bring selected clips into said first location and other selected clips into said second location.
3. The structure recited in claim 2 and means for preventing movement of said auxiliary bar as long as said cam bar is in its first position.
4. The structure recited in claim 2 and locking means for preventing movement of said auxiliary bar, said locking means including a plate carried by said actuating means and having an opening therein, and a pin carried by said cam bar and adapted to engage said opening which said cam bar is moved to its first position to prevent op-

eration of said actuating means as long as said cam bar remains in its first position.

5. The structure recited in claim 2 in which said clips are arranged on said auxiliary bar in groups corresponding to the political parties which will use the machine and in which said auxiliary bar is moved to one position to bring the notches in the wall portions of one group of clips into their first location and to bring other groups of clips to their second location.

6. The structure recited in claim 2 in which said clips are arranged on said auxiliary bar in groups which correspond to the political parties which will use the machine, and locking means for preventing movement of said auxiliary bar when said cam bar is in its first position, said locking means including a plate carried by said actuating means, said plate having spaced holes therein, one for each of said political parties, and a pin carried by said cam bar and adapted to engage one of said holes when said auxiliary bar has been moved to a position to permit operation of the voting spindles assigned to one political party and to engage another of said holes when the auxiliary bar is moved to another position to permit operation of the voting spindles assigned to another political party to prevent operation of said actuating means as long as the voters of any one political party are using the machine.

7. A voting machine including a plurality of vote counters, a plurality of voting spindles, each of said spindles being movable to a first, vote casting, position in which it actuates one of said counters and to a second, non-vote casting, position in which it does not actuate its corresponding vote counter, a vertically movable return member for each of said voting spindles, means operatively connecting each of said return members to a corresponding voting spindle whereby each return member is moved upwardly by movement of its corresponding voting spindle to its first position, and whereby the downward movement of said return member moves said corresponding voting spindle to its second position, an arm carried by each return member, each arm being disposed substantially normal to the vertical plane of movement of the corresponding return member and projecting substantially normal to said plane and each return member and its arm being so related that the arm must move downwardly simultaneously with the upward movement of its corresponding return member, a cam bar located in the path of movement of said arms and having spaced notches therein large enough to receive and permit downward movement of said arms, said cam bar being movable to a first position in which said notches register with said arms to permit downward movement of said arms and upward movement of said return members and to a second position in which said notches do not register with said arm and prevent movement of said arms and of their corresponding return members, a curtain movable to a closed position when said cam bar is in its first position and to an open position when said cam bar is in its second position, a motor for actuating said curtain and means for preventing movement of said curtain to its open position unless at least one of said voting spindles is in vote casting position, said means including a normally open switch electrically connected to said motor, and switch control means operable by the downward movement of any one of said arms to close said switch to energize said motor in curtain opening direction.

8. The structure recited in claim 7 in which said switch control means includes a comb bar and means for mounting said bar for free longitudinal movement relative to said cam bar, said comb bar having spaced teeth disposed in the path of movement of said arms, and having one end tooth disposed adjacent said switch whereby the downward movement of any one of said arms in any of said notches will engage one of said teeth and will move said end tooth in a direction to close said switch.

9. A voting machine including a plurality of vote counters, a plurality of voting spindles for actuating said

counters, a shutter, means mounting said shutter for movement to a first position in which said counters are exposed and to a second position in which said counters are concealed by said shutter, a first, one-way locking device engageable with said shutter to prevent movement thereof to its first position, a second, one-way, locking device engageable with said shutter to prevent movement thereof to its second position, means normally urging each of said locking devices into engagement with said shutter, and release means movable to a first position in which it disengages said first locking device to permit movement of said shutter to its first position, said release means being movable to a second position in which it disengages said second locking device to permit movement of said shutter to its second position.

10. The structure recited in claim 9 and unidirectional locking means for permitting movement of said release means to its first position while preventing movement of said release means to its second position.

11. The structure recited in claim 10 in which said actuating means includes a slide and in which said unidirectional locking means includes a ratchet carried by said slide and a pawl engaging said ratchet in a manner to permit free movement of said slide in a direction to permit movement of said shutter to its first position.

12. The structure recited in claim 10 in which said release means includes a slide bar, in which said unidirectional locking means includes a ratchet carried by said slide bar and a pawl normally engaging said slide bar in a manner to permit movement of said slide bar in a direction to permit movement of said shutter to its first position, and means for disengaging said pawl from said ratchet to permit movement of said slide bar to its second position.

13. A voting machine including a plurality of vote counters, a plurality of voting spindles, means mounting said voting spindles for movement to a first position in which they actuate corresponding vote counters and to a second position in which they do not actuate said counters, a shutter, means mounting said shutter for movement to a first position in which said shutter does not conceal said counters and to a second position in which said shutter conceals said voter counters, locking means for preventing operation of the voting spindles, said locking means including a sliding latch, means for moving said latch to a first position in which said voting spindles are locked and to a second position in which said voting spindles are released for use, there being a hole in said latch, a pin having a reduced body portion and adapted to engage said hole, and a spring normally biasing said pin away from said hole, actuating means movable in a direction to move said shutter from its first to its second position and vice versa, said actuating means including a slide having a key hole slot therein, said slide and said pin being so constructed and related that, when said slide is moved in a direction to move said shutter to its second position, the large portion of the key hole slot registers with said pin and permits movement thereof away from said hole to release said latch, and whereby, when said slide is moved in a direction to move said shutter to its first position, the narrow portion of said slot engages the reduced body portion of said pin and forces it into engagement with said hole against the action of said spring to retain said latch in its locking position, and release means operable by movement of said actuating means in said direction to deactivate said locking means and permit use of the voting spindles.
